UNITED STATES PATENT OFFICE.

FRANK O. CLEMENTS, OF DAYTON, OHIO, ASSIGNOR, BY MESNE ASSIGNMENTS, TO DAYTON-WRIGHT COMPANY, OF DAYTON, OHIO, A CORPORATION OF DELAWARE.

APPARATUS FOR DOPING AIRPLANE WINGS.

Application filed August 28, 1918. Serial No. 251,760.

To all whom it may concern:

Be it known that I, FRANK O. CLEMENTS, a citizen of the United States of America, residing at Dayton, county of Montgomery, 5 State of Ohio, have invented certain new and useful Improvements in Apparatus for Doping Airplane Wings, of which the following is a full, clear, and exact description.

This invention relates to the doping of 10 wings and other parts of airplanes and more particularly to a method of doping those parts without the development of the objectionable "blooming," and to an apparatus for carrying that method into effect.

15 In the manufacture of airplanes, as at present carried on, the wings, the ailerons, the tail and rudder members and parts of the fuselage are covered with fabric. That fabric is coated or impregnated with "dope." 20 This dope normally consists of cellulose compounds, such as nitrates or acetates, dissolved in some solvent, such as amyl acetate, acetone etc. In doping the wings or other fabric covered parts of the airplane the dope 25 solution is applied to the fabric which is then allowed to dry, the solvent evaporating and leaving a film of cellulose material on and within the fabric. If this drying or evaporation takes place in an atmosphere of 30 relatively high humidity some of the component parts of the dope will absorb moisture from the atmosphere and instead of drying in a continuous water-proof membrane or film it will dry as a white, somewhat 35 granular, deposit which looks quite similar to white-wash and is not a weather resisting film nor a water-proof plastic. This phenomenon of doping is called "blooming" and is quite objectionable.

40 The principal object of the present invention is to provide a method of doping airplane fabrics adapted to prevent this blooming, and to provide a practicable form of apparatus for carrying that method into effective operation.

Other objects and advantages of the present invention will be apparent from the description of the invention set out below, in which description reference is made to the 50 accompanying drawing which illustrates several forms of apparatus adapted for carrying out my method of doping.

In the drawings, in which like characters

of reference designate like parts throughout the several views thereof.

55 Fig. 1 is a view partly in elevation and partly in section showing a drying booth used in carrying my method into effect which booth is adapted for receiving a single wing;

60 Fig. 2 is a transverse sectional view of the apparatus of Fig. 1 along the line 2—2 thereof;

65 Fig. 3 is a horizontal sectional view through a modified form of apparatus adapted for receiving three wings at one time; and

70 Fig. 4 is a transverse sectional view through the form of apparatus illustrated in Fig. 3, along the line 4—4 thereof.

75 As stated briefly above, in the present method of airplane manufacture the wings, the ailerons, the tail and rudder members and parts of the fuselage are covered with fabric. In order to give a substantial period of life to this fabric, and to make it stronger and more durable in service, it is necessary to so treat it as to cause shrinkage of the fabric and to make it weather-proof. For 80 treating this fabric a so called "dope" is used, which consists of some cellulose compound, generally cellulose nitrate or cellulose acetate, dissolved in some readily vaporizable solvent, such as amyl acetate or acetone. The dope is generally applied to the fabric by means of brushes, and the 85 present approved practice requires the application of four coats to secure a film or membrane of the desired characteristics. The practice heretofore has been to place the fabric covered pieces of the apparatus in a suitable supporting rack, to apply the 90 dope to the fabric while thus supported and to allow a sufficient time for the drying before applying a second coat of dope. If the relative humidity of the atmosphere in 95 which the doping and drying takes place is low this method is quite satisfactory. If, however, the relative humidity of the atmosphere is high it has been found that during the drying process some moisture 100 from the atmosphere will be absorbed by the dope. This gives rise to blooming. It has been found that these white spots, or 105 blooms, represent cellulose precipitated from solution by water and that such material is granular in form and does not cause proper

shrinkage of the fabric or protect it from the weather.

I have discovered that by properly conditioning the air in which the doped fabric is dried, blooming can be easily prevented. In other words it is merely necessary to so treat the air that the relative humidity thereof may be lowered substantially below saturation. This can be done, of course, in several ways, as for instance by lowering the temperature of the air, before it is used for drying purposes, sufficiently to condense therefrom a substantial portion of the contained moisture. Another and simpler method of accomplishing the same result is to heat the atmospheric air surrounding the wing that is being dried sufficiently to lower the relatively humidity thereof. In other words by raising the temperature of the air, its moisture content remaining constant, the relative humidity of such air will decrease with the increased temperature. Experiment has shown that air, the humidity of which is sufficiently high under existing conditions—the temperature being, say 80 degrees Fahr.—to cause severe blooming will, if the temperature is raised a few degrees, to 95 degrees for example, permit of drying doped wings without the formation of any perceptible blooming whatsoever.

My method in its broad aspect includes any conditioning of the air in which the doped fabrics are to be dried by means of which the relative humidity of such air is lowered sufficiently to prevent blooming. In actual practice, however, I have used, as the simplest and preferred adaptation of my invention, that method of conditioning air which consists of heating the air in order to lower its relative humidity. And for carrying that method into effect I have made use of drying booths containing heating elements adapted to raise the temperature within such booths above the temperature of saturation of the atmospheric air therein.

In carrying out this method I have not found it necessary to use completely closed booths. Instead I have used booths similar to those disclosed in the drawing. Inasmuch as the wings of airplanes because of their unwieldy proportions, of their large expanse of fabric covering and of the necessity for insuring a perfect doping of such fabric, constitute the most difficult phase of the doping operations, and since the proper doping of the wings eradicates the major portion of the doping difficulties, I have illustrated my doping apparatus as adapted for use in the doping of wings. It is of course obvious that the method forming the substance of my invention is applicable not only to the doping of the wing covering but to the doping of fabric used in any other part of the airplane.

And it is equally obvious that with simple

mechanical changes the apparatus disclosed could be adapted for use in connection with any other parts of the airplane.

In Figs. 1 and 2, which illustrate a simple form of apparatus for carrying out my method of doping, 10 is a track carrying member supported from the ceiling by a plurality of beams 11. Any other desired form of supporting mechanism may be used. The member 10, in the form of apparatus heretofore used, is of wood, is substantially 75 12 inches wide and a little more than twice the length of the wing to be doped. This member 10 in addition to being a track carrying member constitutes the upper side 80 of a framework, the other or lower side of the framework consisting of two heavy timbers 12, firmly attached to the floor and braced by means of beams 13. At each end of the member 10 and the beams 12 are located a plurality of uprights 14, there being two of these uprights at each end of the framework, which serve to attach member 10 to the timbers 12, the member 10, the timbers 12 and the uprights 14 thus constituting a rectangular framework substantially twice the length of the wing to be doped, and sufficiently wide to accomodate 90 a single wing.

Carried by the underside of the member 10 is a trolley or track, which as shown 95 consists of two members 20 having inturned flanges 21 adapted to act as a track for receiving the trolley wheels 22. Each of the trolley wheels 22 is rotatably mounted on 100 a shaft 23 which is in turn carried by a standard 24 firmly attached to the upper member 26 of a wing carrying frame 25. As shown the wing carrying frame 25 has attached to the upper side thereof two of 105 the standards 24 and each of these standards carries, on the shaft 23 two trolley wheels 22.

The wing carrying frame 25 consists of a wooden frame composed of wooden parts 26 and 27 which constitute the upper and lower 110 sides of such frame, and of wooden members 28 and 29 which constitute the ends of this frame. Carried by the lower member 27 are a plurality of standards 40 each of which carries a roller 41. The timbers 12 are so placed and the standards 40 and rollers 41 are so mounted on the lower frame member 29 that these rollers cooperate with the inner faces of the timbers 12 which thus 115 constitute guides or tracks to maintain the frame 25 in position as it slides back and forth along the trolley or track 20. Carried by the lower member 27 of the frame 20 are a plurality of supporting blocks 30 upon which the wing to be doped is supported in the frame. Carried by the upper member 26 of the frame 20 is a pivoted supporting block 31. Each of these supporting blocks has therein a groove adapted to receive the edge of the wing to thus hold the 120 125 130

wing firmly and steadily in place within the frame while the dope is being applied to the fabric.

For substantially half its length, extending from one end thereof, the frame work is enclosed so as to form a chamber or booth sufficiently large to completely enclose the track and carrying frame mounted thereon. In actual practice this booth consists of a chamber closed on all four sides and at one end, the other end, the end intermediate the ends of the framework, being open. This booth is of sufficient length to completely receive and enclose the wing carrying frame 15 20 and the wing 50 carried thereby. Located within the booth, which is designated by the numeral 55 are heating coils 60 adapted to receive steam or hot water for raising the temperature of the atmosphere 20 within the booth. The flow of steam or hot water through the heating coils 60 is controlled by a valve 61 by means of which the temperature within the booth may be properly regulated. If desired thermostatic 25 means for controlling the valve 61 to automatically maintain a predetermined temperature in the booth may be used, but such controlling means is not a necessity.

Leading off from the top of the booth and from the bottom thereof are a plurality of ventilating pipes 70 each of which opens into a main 71, which is in turn operatively connected with a pump or blower of some conventional kind (not shown) adapted to 35 remove from the booth the solvent material evaporated during the drying of the dope.

As shown in Fig. 1 of the drawing, that part of the framework which is not surrounded by the booth 55 is broken away. 40 This part of the frame work, however, is of sufficient length to accommodate the entire wing carrying frame 25. When it is desired to dope a wing, the wing carrying frame 25 is slid outwardly along the track 20 until it is completely without the booth. The wing 45 is then placed in the supporting blocks 30, the upper pivoted supporting block 31 being swung upon its pivot to permit of proper positioning of the wing, after which this 50 block is moved into contact with the wing which is in this manner held firmly in place during the doping operations.

In doping with this type of apparatus, the operators stand adjacent the open end of the booth 55 and apply the dope to the fabric covering by means of hand or air brushes. If desired mechanical means for applying the dope, such as mechanically operated brushes, may be used in place of manual 60 means. As the dope is applied to the fabric the frame 25 is moved along the track and into the booth, so that the doped portions of the wing will dry in the conditioned atmosphere within the booth.

65 In Figs. 3 and 4 I have shown a modified

form of apparatus for carrying this method into effect, the principal difference between this form of apparatus and that disclosed in Fig. 1 being that a plurality of wings may be treated in a single piece of apparatus, to 70 thus increase the speed with which these wings may be completely doped and dried. As illustrated in Figs. 3 and 4, this modified form of apparatus consists of a framework composed of a plurality of beams 80 75 supported upon cooperating uprights 81, these uprights being braced by floor beams 82. This framework, like the framework of the modification shown in Figs. 1 and 2, is 80 rectangular in shape, the length of the framework being a little more than three times the length of the wing, or other piece of apparatus, to be treated therein, and sufficiently wide to accommodate the three carrying 85 frames, arranged in parallel.

Arranged upon the floor intermediate the beams 82 are three tracks 90, each of which extends the entire length of the framework. Each of these tracks carries upon the upper face thereof a rod, or pipe, 91 adapted to 90 serve as the track proper, upon which is supported a wing carrying frame 100, and along which said wing carrying frame is adapted to be slid to assume any desired position throughout the length of the framework. 95

Each of the wing carrying frames 100 consists of a rectangular wooden frame, similar to that described above in connection with Fig. 1, having upon the lower member thereof a plurality of supporting blocks, and upon the upper member a pivoted supporting block, for holding the wing steadily within the frame. Each of the wing carrying frames has mounted upon the lower 100 member thereof a plurality of rollers 101, each of which is rotatably mounted upon a shaft 102, carried by the members 103 which are in turn rigidly attached to the lower member of the frame. Attached to each of the members 103 is a guard or protector 104 adapted to overlie the rollers 101 and the track 90, to prevent any dope falling thereupon and interfering with the ready working of the device. Also carried by the wing carrying frame 100 and rigidly attached to the upper member thereof are a plurality of standards 105, each of which carries two rollers 106. These rollers are so positioned with reference to the framework members 100 105 that when in operative position they contact with such members 80, which thus serve as guides and hold the wing carrying frame 110 properly positioned upon the track 90.

In this modification of the device two drying booths are provided. One of these, 110, extends from one end of the framework and incloses a sufficient length of the entire framework, including the three tracks with 115 in the framework, to house completely three 120

of the wing carrying frames. The other of these booths, 115, is located intermediate the ends of the framework and is so positioned with reference to the first mentioned booth that a space 140 between the adjacent ends of the two is left, which is sufficiently large to accommodate two workmen or operators, one upon each side of the tracks. This booth is of substantially the same length as the first mentioned booth, 110, being thus of such size as to inclose completely the three tracks and three of the wing carrying frames. The booth 110 has one end completely closed as shown in the drawing at 111, its other end being open as is the case with the single booth shown in Figs. 1 and 2. The booth 115 has the end thereof adjacent the end of the booth 110 also open. Its other end is not permanently closed, but is provided with a plurality of swinging doors 116, one for each of the tracks 90. These doors may be swung open to permit of sliding the wing carrying frames along the tracks into the booth 115, and, after such wing carrying frames are completely within the booth, may be closed, thus leaving this booth open at only one end, as is the case with booth 110. The entire length of the framework is such that a sufficient length of it is uninclosed, beyond the door end of the booth 115, to accommodate upon each track, in such uninclosed portion, an entire wing carrying frame 100.

The booths 110 and 115 have heating coils 120 therein, the flow of steam, hot water or other heating medium within these coils being controlled by means of valves 121. If desired the valves 121 may be controlled by thermostatic means to automatically maintain a predetermined temperature within the booth.

Leading off from the booths 110 and 115 are ventilating pipes 130, each of which leads into the ventilating main 131 which has therein a blower, or pump, (not shown), of any conventional type for removing from the booths the solvent laden atmosphere resulting from the drying of the doped wings.

As in Figs. 1 and 2, the apparatus is shown as partly broken away in order to disclose the entire apparatus in one view.

The same method of doping may of course be carried out in both types of apparatus disclosed and described above. As stated above, in the present accepted practice in airplane construction, each wing or other fabric-covered part of an airplane which is treated with dope is given four coats of the dope, after which it is enameled. With the apparatus shown in Fig. 1, a wing is mounted within the wing carrying frame and doped as the frame is gradually moved forward carrying the doped part of the wing into the drying booth. After the doping is completed the wing is left within the dry-

ing booth about 10 minutes to permit of the complete drying out of all the solvent. The wing carrying frame is then drawn out of the booth and the wing given another coating of the dope in exactly the same manner. This process being repeated until the four coats have been applied.

In doping wings in the apparatus disclosed in Figs. 3 and 4 the method is fundamentally the same, but because of structural differences this doping apparatus lends itself to more efficient carrying on of the work. In using this type of apparatus the three wing carrying frames are moved to the uninclosed portion of the framework and the wings to be doped are mounted therein. The doors 116 are then opened and the three frames, with the wings therein, are moved into the booth 115. The doors 116 are then closed. The operators stand in the space 140 between the two booths 110 and 115. The wings are gradually moved, one at a time, from the booth 115 to the booth 110, the two operators doping the two sides of the wing as it passes through the space 140. The three wings are worked from the booth 115 to the booth 110 in succession, each wing being completely doped as it passes between the two operators. In ordinary practice it takes about five minutes to dope a complete wing with two operators working upon it. By the time the third wing is completely doped the first wing has been within the drying booth for ten minutes and is therefore completely dry and ready for the second coating. The wings are then moved successively from booth 110 back into booth 115 being again doped as they pass through the space 140. And this operation is repeated until each wing has received four coats and is completely doped. At the close of this doping operation the three wings will be in booth 115. It is therefore merely necessary to allow a ten-minute dwell to permit of the complete drying of the last wing, after which the doors 116 are opened, the wing carrying frames slid out upon the uninclosed portion of the tracks, the wings removed therefrom, new wings mounted in the frames to take their places and the sequence of doping operations resumed. It is obvious that this form of doping apparatus lends itself to very efficient work. It is equally obvious that the number of tracks within the drying booths, and therefore the number of wings which may be included in one sequence of doping operations, is purely a question of expediency. And this number may be increased or decreased as desired, to secure the best results; a greater number being advisable if the length of time necessary for doping and drying can be reduced, and a smaller number advisable if the doping and drying period as set out above is found insufficient.

While I have described my method of doping to prevent blooming in connection with apparatus comprising heating coils for lowering the relative humidity of the drying atmosphere, I wish it expressly understood that it is by no means limited to this specific means of securing this desired result. Obviously other means for lowering the relative humidity of the drying atmosphere 10 might be devised, such a means for instance being, as stated above, a refrigerating apparatus for condensing the moisture in the atmosphere before it is introduced into the drying booths, and my invention therefore 15 is not to be limited in its scope to this precise disclosure.

While the method herein described, and the forms of apparatus for carrying this method into effect, constitute preferred embodiments of the invention, it is to be understood that the invention is not limited to this precise method and apparatus, and that changes may be made in either without departing from the scope of the invention 25 which is defined in the appended claims.

What I claim is as follows:

1. In an apparatus for doping the fabric covering of airplane parts, a track; a frame 30 slidably mounted on said track and adapted

for carrying therein the part to be doped; and a plurality of booths surrounding said track, each booth adapted to receive and completely house the frame.

2. In an apparatus for doping the fabric covering of airplane parts, a track; a frame 35 slidably mounted on said track and adapted for carrying therein the part to be doped; a plurality of booths surrounding said track and spaced from each other; a portion of said track lying outside of said booths and 40 of greater length than the frame.

3. In an apparatus for doping the fabric covering of airplane parts, a plurality of tracks; a frame for carrying therein the part to be doped, slidably mounted on each 45 track; a plurality of booths spaced from each other, each booth inclosing a portion of all of the tracks; a portion of each track at one end being uninclosed by the booths; and means for opening or closing the end 50 of the booth adjacent the uninclosed portion of the tracks.

In testimony whereof I affix my signature.

FRANK O. CLEMENTS.
